[57] ABSTRACT

In a transfer electrophotographic duplicator an exposure means includes an optical system having a slit movable in parallel with a transparent plate for supporting an original document so as to project an image onto a flexible sensitive film. At least a portion of the film is supported in a plane parallel to the transparent plate by a supply roller and a take-up roller. A driving roller transports the flexible film between the supply roller and the take-up roller and is controlled by a first switch which stops the driving roller when the film has been transported a distance a length longer than that of the original image. A driving member is then actuated to move the exposure means across the transparent plate and a second switch stops the driving member after it has moved across the transparent plate. A third switch actuates the driving roller to transport the film from the take-up roller to the supply roller. Control means are provided for actuating a corona discharge device, a transfer feeding device, a transfer device, and a developing device.

TRANSFER TYPE ELECTROPHOTOGRAPHIC DUPLICATING APPARATUS

BACKGROUND OF THE INVENTION

This invention relates to a transfer type electrophotographic duplicator in which an original picture and a sensitive material are stationary and an exposure optical system moves therebetween to project in turn original picture images.

Transfer type duplicators in the prior art are in general of the dry toner figure transfer type represented by the Carlson system duplicator. However, in such duplicators, a drum-shaped sensitive material is used and the picture image exposure is effected by running an exposure optical system in connection with the circumferential speed of the drum-shaped sensitive material. It is hard to obtain a copy of clear picture quality and the mechanism is complex because of the two moving members therof. Additionally, the duplicator itself is of a very large-size and as a result it must be manufactured into a console form.

On the other hand, in record type duplicators for forming a record directly on a sensitive paper, the so-called electro-fax system duplicators, an original picture and a sensitive paper are stationary and an exposure optical system is moved therebetween to effect a picture image exposure. Thereby a copy of clear picture quality can be obtained, its mechanism is simple, the duplicator itself is small-sized, and many duplicators can be manufactured into a desk type. However, copying paper is used as the sensitive material, so that the paper is thick and accordingly the copying paper is heavy.

SUMMARY OF THE INVENTION

One object of the present invention is to provide a transfer type electrophotographic duplicator in which the sensitive material is planar, and an original picture and the sensitive material are stationary and an exposure optical system is moved to effect exposure and projection. Accordingly dead spaces are reduced and yet a clear picture quality can be obtained.

Another object of the present invention is to provide a transfer type electrophotographic duplicator in which by moving the optical members as described above the whole mechanism is simplified and the duplicator itself is small-sized to fit on top of a desk.

Further another object of the present invention is to provide a transfer type electrophotographic duplicator capable of developing either by wet or dry techniques.

Still another object of the present invention is to provide a transfer type electrophotographic duplicator using a flexible sensitive material quite different in construction and the method of exposure from those in the prior duplicators, and which is very flexible and has reliable sensitive material.

And, the characteristics and the above-mentioned objects of the present invention will be understood more clearly through the detailed description of the invention, the claims, and the accompanying drawings.

BRIEF DESCRIPTION OF THE DRAWINGS:

FIG. 1 is an illustration of the construction and the image forming principle of a sensitive material used in the transfer type electrophotographic duplicator in accordance with the present invention.

FIG. 2 is a side view showing an outline of an electrostatic latent image forming portion of a duplicator in accordance with the present invention.

FIG. 3 is a side view showing an outline of one embodiment in accordance with the present invention.

FIG. 4 is a detailed view of the essential portion of a carrying roller for the sensitive material of the embodiment of FIG. 3.

FIG. 5 is a diagram of an electric circuit for the embodiment of FIG. 3.

FIG. 6 is a time chart for illustrating the time function of the essential portion of the embodiment of FIG. 3.

FIG. 7 is a side view showing an outline of another embodiment of a duplicator in accordance with the present invention.

FIGS. 8A and 8B are respectively sectional views of the developing portion of the embodiment of FIG. 7, wherein FIG. 8A shows the components at the developing time and FIG. 8B shows the components at the non-developing time.

FIG. 9 is a perspective view showing one example of a developing device of the embodiment of FIG. 7.

FIG. 10 is a diagram of an electric circuit for the embodiment of FIG. 7.

FIG. 11 is an illustration of the time function of the essential portion of the embodiment of FIG. 7.

DETAILED DESCRIPTION OF THE INVENTION:

In FIG. 1 the construction and the image forming principle of a sensitive material used in a duplicator in accordance with the present invention are illustrated.

FIG. 1 shows one embodiment of a sensitive material P so formed that for example, onto flexible transparent support a made of a polyester film of 75 μ thickness, thin film b made of a conductive material of less than 1 μ thickness is evaporated, and thereon there is formed a thin film c (can contain Te in less than 7 percent by weight ratio) formed by evaporating a photosemiconductor such as non-crystalline Se of 1 μ or so thickness. Further thereon there is coated a flexible high resistance organic semiconductive film d formed by applying an organic semiconductor from 10 to 15 μ dry film thickness containing polyvinylcarbazole using diphenylthiocarbazone trichloride as a plasticizer and monochlorobenzene as a solvent. The polyvinylcarbazole can contain a very little silicone as the characteristic of electrophotographic image forming is not affected and in this case diphenylthiocarbazone trichloride is not used.

Now, as shown in the drawing, when on flexible high resistance organic photosemiconductive film d a negative electric charge is placed and exposed from the polyester film a side as shown by the arrow, Se thin film c is photo-excited by light passing through b thin film b and positive holes generated thereby flow to the organic photosemiconductor d side by the negative electric charge on the surface, pass through organic photosemiconductor film d and move to the surface as shown in the drawing to neutralize the negative electric charge on the surface. Also, thin film Se forms a high rectification barrier at the interface of Se thin film c to prevent positive holes from moving to Se thin film c, and thereby an electrostatic latent image having improved picture image concentration and contrast is formed. And thus, a sensitive film practical as a transfer type sensitive material is obtained, wherein thin film b and Se thin film c are less than 1 μ or so in thickness,

and PVK film *d* and polyester film *a* are made of macro-molecule material. And, thin film *b* and Se evaporation film *c* can be strongly adhered by exposing thin film *b* in a glow discharge to give a forced oxidation through ion bombardment and then vacuum evaporating the Se. Therefore, for example even though this sensitive material is formed into a belt-shape and put over two rollers of 30 mm ϕ to be rotated at a high speed such as 1 m/s for 1000 hours no exfoliation takes place between film *b* and Se film *c*, and it is possible to use the photosensitive material as a belt-shaped sensitive sheet or as a roll-shaped sensitive film.

Further, the construction of the sensitive film used in the duplicator in accordance with the present invention is functionally described hereinafter. The flexible sensitive film is formed by layering in order onto flexible transparent support *a*, thin film *b* made of a conductive material which is an electrode of very thin thickness and having a transmission factor above 50 percent, and contacts with photosemiconductive film *c* to form a high rectifying barrier for preventing electric charge from migrating into film *c*. A very thin organic photosemiconductive film *c* the whole of which absorbs light to generate electric charge carriers, and a flexible high resistance semiconductor film *d* functioning as a passage for the electric charge carriers generated by photosemiconductive film *c* are also deposited. And accordingly, the flexible sensitive film is quite different in construction, the mechanism for sensitizing, and in the image exposure direction from sensitive film or sensitive papers used in the prior art duplicators. The sensitive film is strong, has good flexibility, and is able to charge to a high potential of 1000V or more and effect picture image exposure to a high sensitivity as from 10 to 30 Lux-Sec. Additionally, it has very little pre-exposure effect, and thus it is possible to form an electrostatic latent image of high contrast and high resolving power.

FIG. 2 shows the construction of the original picture image forming portion of the duplicator in accordance with the present invention, making use of sensitive film *P* in which the flexible sensitive film is formed into a roll-shape. In FIG. 2, relative to stationary original picture *O* sensitive film *P* is disposed with flexible high resistance semiconductor film *d* facing down and both ends thereof are respectively wound around rolls 1 and 2. Rolls 1 and 2 are energized respectively in the direction to take up the film weakly by a spring means not shown in the drawing, and film *P* is evenly disposed by two rollers 3 for keeping it in a plane and carried by carrying roller 4. Between original picture *O* and sensitive film *P*, there is disposed in parallel therewith to oscillate with original picture length exposure means *B* constituting erect optical system *L* having, for example, irradiation lamp *I* with a reflecting shape, one mirror lens, and two reflecting mirrors in a body and providing a slit; and on the down side of sensitive film *P* there is disposed stationary corona discharge device *A* for uniformly charging flexible high resistance semiconductive film *d*.

Now, in the case of original picture image forming, as sensitive film *P* is carried a certain length from supply roll 1 to the take-up roll 2 side by rotating carrying roller 4, flexible high resistance semiconductive film *d* is uniformly charged by corona discharge device *A*. The film is stopped and maintained in a plane and in parallel with original picture *O* by means of rollers 3.

Then slit exposure means *B* is moved in the direction shown by the arrow and thereby the picture image of original picture *O* irradiated by irradiation light source *I* is projected on transparent support film *a* on the back side of sensitive film *P* through erect optical system *L*. An electrostatic latent image corresponding to original picture *O* is formed on the surface of sensitive film *P*. Subsequently upon rotating roller 4 sensitive film *P* is carried into position for effecting transfer.

By forming the apparatus as described above, the whole mechanism thereof is very simple and in addition the following advantages are gained: as compared with the prior art transfer type duplicator the duplicator itself can be small-sized and used as a desk type, and when an image is formed the original picture and the sensitive body are both stationary, so that a copy of clear picture quality can be expected.

Next, an embodiment of the whole transfer type duplicator provided with the original picture image forming portion formed as described above is described.

FIG. 3 shows an electrostatic latent image type duplicating apparatus, wherein parts corresponding to the parts shown in FIG. 2 are designated the same.

In FIG. 3, on the top of duplicator case body 5 original glass base plate 6 is provided and exposure means *B* is provided so as to move parallel to glass base 6 by means of guide rail 8 through roller 7 provided rotatably on the side of exposure means *B* cable 10 both ends of which are fastened respectively to two pins 9 provided on the side of exposure means *B* are wound over pulley 11 for driving motor MB and driven pulley 12. Thereby exposure means *B* can be moved in the direction shown by the arrow through rotation of motor MB, and when return switch SWR is switched off motor MB is stopped and at the same time exposure means *B* is returned to the original position by return spring 13 provided between the left side wall of the duplicator case body and exposure means *B*.

Carrying roller 4 is provided to rotate in either direction using driving motor MP as a driving source and also to turn cam 14 as shown in FIG. 4. On the circumference of cam 14 there are disposed micro-switches SWA1, SWA2, and SWA3 which are respectively actuated by projection 14a of cam 14.

Driven roller 4' is composed of a grounded conductive member, and in the embodiment, for both rollers 4 and 4' a conductive rubber roller is used to constitute latent image transfer portion *K*. Transfer paper *T* piled on transfer paper base 15 is formed by applying onto a paper of 100 μ or so thickness a conductive treatment to a high dielectric material such as polyethylene, wax, alkyd resin, cellulose acetate, epoxide. Further a resin film such as vinyl chloride vinyl acetate copolymer up to 2 to 10 μ thickness is also formed thereon, and delivered singly by feed roller 16 driven by motor MT. However, it is understood that the delivery time is set so as to be controlled in accordance with the movement of sensitive film *P*, and the electrostatic latent image forming portion on sensitive film *P* and the tip of transfer paper *T* are controlled to be carried concurrently to the clearance between both rollers 4 and 4'.

Liquid developing device *D* mounted in the after position of the transfer mechanism is provided with well known, for example, a pair of delivery rollers 17, guide plate and concurrently developer saucer 18, electrode 19, developer tank 20, developer supply means for supplying the developer in tank 20 to saucer 18 which

passes through pipe 22 by means of pump 21 driven by motor MD shown in FIG. 5. Excess developer is returned to tank 20 from the side of saucer 18, and a pair of throttle rollers 23 are also provided. In the rear of developing device there is disposed dry fixing device F composed of heater H and a blower driven by motor MD, and under it conveyor belt 25 is disposed for carrying transfer paper T while drying it to copy receiving plate 24 provided on the side plate of duplicator case body 5. And delivery rollers 17, throttle rollers 23, and conveyor belt 25 are driven by motor MR through a well known transmission means not shown in the drawing.

Reference numeral 26 denotes a light intercepting screen spread between side plates of exposure means B and case body 5.

The electric circuit of the duplicator is connected as shown in FIG. 5, and main switch SM and start switch SS are provided in a position accessible to be manipulated from the outside.

In operation, upon switching main switch ON motors MR, MD, and MF are driven and simultaneously heater H is lit, rollers 17 and 23 and conveyor belt 25 are rotated, and the developer in developing device D is circulated.

When duplicating is initiated, upon putting original picture O on glass base 6 and pressing start switch SS exciting coil RY1_A of one side of relay RY1 is electrified through contact SSA and all contacts from 1A to 4A of relay RY1 are respectively switched-over to contacts a and rectifier S is electrified by contact piece 2B through closed contact SSB. Thereby motor MP is rotated in the normal direction to rotate carrying roller 4 clockwise in FIG. 2 and FIG. 3.

Through the rotation of carrying roller 4 sensitive film P is carried to the roll 2 side and cam 14 is turned rotated, and as cam 14 is turned its projection 14a operates micro-switches SWA₁ and SWA₂ to switch them to contacts a, and even though start switch SS is released motor MP continues to rotate. On the other hand, high tension transformer CH also is operated through contacts 3A and 3B of the relay switch and corona discharge device A is still kept operative.

Therefore, sensitive film P is carried while flexible high resistance semiconductive film d is charged by corona discharge device A and when semiconductive film d is carried a predetermined length projection 14a of cam 14 operates microswitch SWB, so that relay RY2 is excited, all contacts from 1B to 4B thereof are respectively switched-over to contact b, relay RY2 is self-held through contact 1B, and thereby contact 2B stops the rotation of motor MP and relay contact piece 4B cuts off high tension transformer CH to stop the discharging of corona discharge device A. Simultaneously therewith, light source I is lit through contact 3B, motor MB is started, and exposure means B is moved in the direction shown by the arrow to project the picture image of original picture O in turn onto the back side of sensitive film P. Thus an electrostatic latent image of the mirror image corresponding to the original picture is formed on flexible high resistance semiconductive film d on the surface of the sensitive film.

Just as exposure means B switches return switch SWR to the contact a side and the self-holding of relay RY2 is cut off, and accordingly all contacts from 1B to 4B thereof are returned so as to light source I, and

motor M stops and exposure means B is returned to its original position by means of spring 13.

Also, at the same time exciting coil RY1_B of the other side of relay RY1 is electrified, so that all contacts from 1A to 4A of relay RY1 are switched-over the contact b side, motor MP is rotated in the reverse direction, carrying roller 4 starts to rotate in the opposite, sensitive film P is carried to the roll 1 side, cam 14 is rotated in the opposite direction, at the same time motor MT is rotated by contact 4A and transfer paper T is delivered by feed roller 16.

Sensitive film P and transfer paper T are interposed between carrying roller 4 and driven roller 4' so that they come into close contact with each other, and the electrostatic latent image on sensitive film P is transferred in turn onto transfer paper T.

After transfer, cam 14 is returned to its original position and projection 14a operates microswitches SWA₁ and SWA₂, and when both switches SWA₁ and SWA₂ are switched-over to contact b the rotation of motor MP is stopped, carrying roller 4 is stopped, and sensitive film P is returned to its original position.

Further, transfer paper T on which the electrostatic latent image is transferred is carried to liquid developing device D by roller 17 and toner is applied to the latent image between saucer 18 and electrode 19 to develop it, and then transfer paper T is carried onto conveyor belt 25 while excess developer is removed by throttle rollers 23. The transfer paper is then carried to copy receiving plate 24 while it is dried and fixed on the belt by the dry fixing device F.

Meanwhile, the time functions of high tension transformer CH, sensitive body film P, exposure means B, and transfer paper T are as shown in FIG. 6.

As described above, in duplicating sensitive film P it reciprocates between rolls 1 and 2 by means of carrying roller 4 and driven roller 4' and the same film face is repeatedly used effectively.

Besides, when sensitive film P is worn out, by manually moving take-up roll 2 one original picture length portion it is possible to use the unused film face repeatedly as described above.

And, in the duplicating apparatus, by forming corona discharge device A in a body with exposure device B in the position shown by the one point chain line in FIG. 3 and making the connection of high tension transformer CH as shown by the one point chain line in FIG. 5 so as to operate simultaneously the lighting of light source I it is also possible to omit relay contacts 3A and 4B.

As described above, by forming a latent image transfer type duplicator, as compared with the prior art transfer type duplicators such as a drum sensitive body type, a picture image of very high quality can be made, a sensitive body film can be used effectively. Further exchanging of the films is very simple, and in addition the sensitive body film can be reciprocated in one plane, so that dead space is minimized and a desk type duplicator nearly the same size as prior electrofax type duplicators can be obtained. Also the copy obtained is of high quality by virtue of the ultrafine grain characteristic of a liquid developer.

FIG. 7 shows an embodiment of a dry toner transfer type wherein the parts corresponding to those in FIG. 3 are denoted by the same designations.

In this duplicator, transfer paper T can be conventional paper such as is used in a xerography type dupli-

cator, and a dry type developer is used. For example as shown in FIG. 9, rotary roller 27 and opposite polarity plate 28 constitute the developing portion and for sensitive film P a magnetic material is used. Between both ends thereof permanent magnets 29 are disposed to magnetize rotary roller 27 and opposite plate 28 to different polarities so as to generate a magnetic flux. A dry developing device D' is used which is so formed that developer 30 composed of magnetic carriers produced by the magnetic flux and toner is stored in developer tank 31, and for controlling the magnetic brush, relative to rotary roller 27 angled permanent magnetic piece 32 is provided on the outside of developer tank 31 to rotate 90 degrees by means of solenoid R which is rotated 90 degrees and provided with return spiral spring 33.

FIG. 8A shows the state in which the magnetic brush is formed by permanent magnetic piece 32 and sensitive film P is being developed, and FIG. 8B shows the state in which the formation of the magnetic brush is stopped. Developing device D' is disposed between corona discharge device A and transfer corona discharge device C opposite carrying roller 4.

On the magnetic piece 32 side and diagonally under rotary roller 27 pulsator 34 made of a non-magnetic material and rotatable in the reverse direction as rotary roller 27 is disposed to splash up developer 30 stored on the bottom of developer tank 31 and thereby the transportation of developer 30 is aided.

And, roll 1 is positioned a little higher than carrying roller 4 so that sensitive film P may separate of itself from transfer paper T, and onto the sensitive film P cleaner 35 is applied. And, corona discharge device A is provided in a body with exposure means B as described above and for a fixing device thermal fixing device F' provided with heater H' is used. In the front of transfer corona discharge device C delivery roller 36 for transfer paper T is provided, which is connected to carrying roller 4 to be driven by any well known means.

As shown in FIG. 10, in this circuit high voltage generating transformer CH for corona discharge device A and light source 1 are connected in parallel with contact b 3B of relay switch RY2. Rotary solenoid R and feed motor MT are connected in parallel with contact 4A of relay RY1, transfer corona discharge device C is serially connected to microswitches MS1 and MS2, and driving motor MD' for rotary roller 27 for developing device D', thermal source H' for thermal fixing device F', fan MF', and cleaner 35 are parallelly connected with each other and directly connected to main switch SM. The other components are the same as those in the duplicator described previously.

In the operation of this duplicator, as compared with the latent image transfer type described above, corona discharge device A operates simultaneously with light source 1, the developing and the transfer mechanisms are operated when roller 4 is reversely rotated, and the other mechanisms operate in the same manner as in the latent image type.

First of all, when start switch SS is pushed and sensitive film P is carried to the roll 2 side through the normal rotation of carrying roller 4, in the developing device, as shown in FIG. 8B permanent magnet 32 is energized by spiral spring 33, the same polarity faces rotary roller 27, and no magnetic brush is developed between rotary roller 27 and 32.

When the sensitive film P is stopped, micro-switch SWB is operated by the cam, so that on sensitive film P uniform charging and image exposure are effected only for the moving distance of exposure means B and an electrostatic latent image is formed. When sensitive film P is carried to the roll 1 side through the inverse rotation of carrying roller 4, simultaneously with the feeding of transfer paper T rotary solenoid R is electrified to rotate 90 degrees against the energy of spring 33. And as shown in FIG. 8A magnet 32 is rotated so as to of a different polarity from rotary roller 27, and thereby a magnetic brush is produced between magnet 32 and rotary roller 37, therefore, between opposite plate 28 and rotary roller 27 the magnetic brush of the developer is enhanced to develop the electrostatic latent image on the sensitive film. Additionally, the tip of transfer paper T trips microswitch MS1 located just before delivery roller 36 to operate transfer corona discharge device C and the paper passes by corona discharge device C while being in close contact with the film face developed by delivery roller 36. In this case, the dry toner figure is transferred from the sensitive film face to transfer paper T and transfer paper T is automatically separated from the sensitive film face by its tension and dead load when sensitive film P changes its direction and guided to conveyor belt 25 and carried to saucer 24 while being fixed by thermal fixing device F'. Then, sensitive film P is cleaned of the remaining toner by cleaner 35 before being taken up by roll 1.

And, driving motor MD' for developing device D' can be connected to feed motor MT so as to be operated simultaneously therewith as shown by the one point chain line in FIG. 10. In this case, the time function of the respective essential components is shown in FIG. 11.

As described above, even though constructed as a dry toner figure transfer type duplicator, as compared with the prior duplicators in the present invention it is possible to obtain picture image copies of very high quality, the sensitive film can be used effectively, exchanging films is very simple, dead space is very little, and a desk type duplicator can be easily manufactured.

Besides, in this embodiment or the first embodiment described above, in the case where the corona discharge device A is provided in a body with exposure means B it is understood that as a transfer paper a roll-shaped paper is put to use, the location of return switch SWR is changed corresponding to the size of original picture O, transfer paper T is fed simultaneously with the movement of exposure means B, and just when switch SWR is operated the paper is cut by a cutter, so that the sensitive film and the transfer paper can be effectively used even when the size of original picture O is changed.

I claim:

1. A transfer type electrophotographic duplicator, comprising:

a transparent plate for supporting an original document;

exposure means including a light source for illuminating said original document, an optical system for projecting the positive image of said original and a slit for transmitting the projected image movable between the ends of said transparent plate in parallel therewith;

a driving member for driving said exposure means; a flexible sensitive film;

a supply roller and take-up roller for winding respective opposite ends of said flexible sensitive film and rotatably pivoted at respective positions on opposite sides of said exposure means for supporting said flexible sensitive film parallel to said transparent plate;

a driving roller for transferring said flexible sensitive film between said supply roller and said take-up roller;

a charging device for charging said flexible sensitive film; 10

means for feeding transfer paper;

means for transferring the image formed on said flexible sensitive film to said transfer paper as a positive image; 15

a device for developing the transferred positive image on said transfer paper;

first switching means for stopping the rotation of said driving roller when said driving roller transfers said flexible sensitive film a distance a length longer than that of said original image; 20

means for actuating said driving member with the stopping of said driving roller so as to drive said exposure means across said transparent plate;

second switching means for stopping said driving member operated by said exposure means when said exposure means is driven to the other end of said transparent plate; 25

third switching means for actuating said driving roller to transfer the flexible sensitive film from said take-up roller to said supply roller with the operation of said second switching means; and 30

a member for actuating said means for feeding transfer papers in interlocking relationship with said third switching means.

2. A transfer type electrophotographic duplicator as in claim 1, wherein said charging device is mounted at a position spaced outside of the movement of said exposure means, and fourth switching means for actuating said charging device when said flexible sensitive film is transferred from said supply roller to said take-up roller for charging said film.

3. A transfer type electrophotographic duplicator as in claim 1, wherein said transfer means is a transfer roller cooperating with said driving roller for pressing said transfer paper to said flexible sensitive film to transfer the electrostatic latent image on said film to the transfer paper, and said developing device is a wet type developing device.

4. A transfer type electrophotographic duplicator as in claim 1, wherein said charging device is movable along said film with said exposure means, and fifth switching means for actuating said charging device for charging said film uniformly as said driving member drives said exposure means.

5. A transfer type electrophotographic duplicator as in claim 4, wherein said transfer means is a transfer roller cooperating with said driving roller for pressing said transfer paper to said flexible sensitive film to transfer the electrostatic latent image on said film to the transfer paper, and said developing device is a wet type developing device.
